UNITED STATES PATENT OFFICE.

WILLIAM B. DONNELL, OF ORANGE, NEW JERSEY.

CHEMICAL-ENGINE.

SPECIFICATION forming part of Letters Patent No. 788,892, dated May 2, 1905.

Application filed April 11, 1904. Serial No. 202,693.

To all whom it may concern:

Be it known that I, WILLIAM B. DONNELL, a citizen of the United States of America, and a resident of Orange, in the county of Essex and State of New Jersey, have invented certain new and useful Improvements in Chemical-Engines, of which the following is a specification.

This invention relates in general to improvements in chemical-engines of the kind employed by fire departments, and specifically to a by-pass connecting the chemical-tanks of such engine for controlling the flow of liquids to and from the tanks, and also for making a direct waterway from the receiver or inlet to the delivery-pipe.

The object of the invention is to construct a by-pass wherein all the valves thereof are compactly arranged in a vertical plane and located approximately within the area of the front end of the tanks, so that they will be readily accessible from the front end of the tanks or one side of the engine; also, to reduce the number of valves as at present employed in such by-passes and give a more direct passage to the incoming and outgoing liquids, thereby reducing the friction occasioned by the many angles in the by-passes now in use. The receiver or inlet end of the by-pass has the standard fire-department thread, so that the hose of said department can be attached thereto at will when it is desired to refill the chemical-tanks or use the direct water-pipe, which is connected to the delivery-pipe of the tanks. Heretofore in the construction of by-passes for this purpose much trouble has been experienced by not having the valves controlling the same centralized—that is, some of the by-passes are arranged on the tops of the tanks, where the valves are difficult to reach, while some of them are so arranged that the valves are located at opposite ends of the tank, making it very confusing to understand their use. In the former construction of by-passes the supply-inlet was of the same area as the tank-supplying pipes, whereas it should be at least three to one to insure a rapid filling of the tanks and a good serviceable water-stream of

adequate pressure through the direct water-way to the delivery-pipe. The former by-passes have also been deficient in that the pipes have not been arranged with regard to giving the least possible amount of friction, the liquid having in many instances to make from four to six sharp turns before it reaches the delivery-hose. By constructing a by-pass in the manner hereinafter fully explained these objectionable features are overcome and a by-pass constructed wherein the inlet area is of sufficient capacity to supply adequately the three pipes connected, respectively, with the two tanks and the delivery-hose and wherein it is only necessary to employ five valves to accomplish what has heretofore required more valves and also to centralize said valves within a limited space at one end of the tanks and accessible for the operator to control while standing on the ground at the side of the engine.

My improvement comprises two horizontally-arranged revoluble tanks, horizontal pipes extending forwardly from the axes of tanks, hand-wheels fixed to the horizontal pipes whereby the tanks are revolved, stuffing-boxes in which the outer ends of the horizontal pipes are journaled, and a by-pass located in a vertical plane approximately within the area of the front end of the tanks, supported by the stuffing-boxes upon the horizontal pipes and consisting of an upper pipe located in the same plane as the horizontal pipes having elbow-couplings connected with the stuffing-boxes, T-couplings connected with the elbow-couplings, valved couplings having valves and connected with the T-couplings, and a cross-coupling for a delivery-pipe connecting the valved couplings, depending pipes connected with the T-couplings, a lower pipe having elbow-couplings connected to the lower end of the depending pipes, valved couplings having valves and connected to the elbow-couplings, and a cross-coupling for the supply-pipe connecting the valved couplings, and a vertical valved coupling having a valve and connecting the cross-couplings, all as hereinafter described and claimed.

In order that my invention may be fully

understood, I will proceed to describe it with reference to the accompanying drawings, in which—

Figure 1 is an end elevation showing the 5 by-pass connected to the front end of two horizontally-arranged chemical-tanks. Fig. 2 is a side view of the same.

1 1 are two chemical-tanks, which are suitably supported in horizontal position on the 10 body of the engine in any desirable manner. (Not shown.) 2 represents horizontal leading-out pipes from the axes of same, to the outer ends of which are secured hand-wheels 3, said hand-wheels being employed to revolve 15 the tanks when it is necessary to put them in action.

4 represents stuffing-boxes connecting the by-pass with and supporting it on the leading-out pipes 2 and permit the leading-out pipes 20 2 to be journaled in and form a rotatable connection with said by-pass.

5 is a T-coupling connected with an upper elbow-coupling 4', secured to a stuffing-box 4 and providing the outlet-pipe from the left-hand tank, and 5' is another T-coupling connected to another upper elbow-coupling 4', secured to the other stuffing-box 4 and providing the outlet-pipe from the right-hand tank.

30 Each of the pipes has communication with an upper valved coupling 6, having vertical valves 6', which are controlled by hand-wheels 7. These upper valved couplings 6 are joined by an upper cross-coupling 8 to the delivery-pipe 9, located between the upper valved couplings 6.

Connected, respectively, with the T-couplings 5 and 5', between the upper valved couplings 6 and the upper elbow-couplings 4', are 40 the supply-pipes 10 10'. These pipes project downwardly from the T-couplings 5 and 5' and are connected at their lower ends by means of lower elbow-couplings 4" and lower valved couplings 14 with a cross-coupling 11, connected with the main supply-pipe 12. Located 45 in the valved couplings 14 are horizontal valves 14', which are controlled by hand-wheels 15. Connected with the upper cross-coupling 8 and the lower cross-coupling 11 is a water-valved coupling 17, which has located therein, between the cross-couplings 8 and 11, a valve 18, controlled by a hand-wheel 19. It will be understood that the main supply-pipe 12 is of sufficient area to supply equally the lower 55 valved couplings 14 and the depending pipes 10 10' and valved couplings 17 when the controlling-valves of said valved couplings are open to permit water to flow into the tanks and directly to the delivery-pipe 9. This is a 60 very important feature in the present invention, inasmuch as it allows water to be applied to the delivery-pipe with sufficient pressure to be of value without diminishing the pressure in the depending supply-pipes 10 and 65 10' while they are refilling the chemical-tanks.

When it is desired to fill or refill the chemical-tanks, the vertical valves 6' of the upper valved couplings 6 are first closed, which will cut off communication with the delivery-pipe 9. The valve 18 in the vertical valved coupling 17 is also closed, which will prevent the water from passing directly to the delivery-pipe 9. The valves 14' in the lowered valved couplings 14 are then opened, which will permit the water to flow through the lower elbow-couplings 4" and the depending supply-pipes 10 and 10' to the T-couplings 5 and 5' and elbow-couplings 4' and thence through the horizontal pipes 2 to the chemical-tanks. When the tanks are filled, the valves 14' of the lower valved couplings 14 are closed, whereupon the engine is in condition to be used.

When it is desired to use one of the tanks, (presuming it to be the left-hand tank in Fig. 1,) the hand-wheel 3 thereof is turned, which will rotate the said tank 1 and generate the desired gases in the usual manner. The vertical valve 6' of the left-hand upper valved coupling 6 is then opened, whereupon the delivery-pipe 9 will discharge the liquid (after receiving it through the left-hand T-coupling 5 and the left-hand upper valved coupling 6) to the chemical-hose. (Not shown.) When the left-hand tank is empty, the vertical valve 6' in the left-hand upper valved coupling 6 can be closed and the valve 6' of the right-hand upper valved coupling 6 be opened in the same manner, which will continue the supply of liquid to the delivery-pipe 9 from tank 1 on the right-hand side after it has been placed in action in the same manner as has been the tank on the left-hand side. While the tank on the right-hand side is being exhausted, valve 14' of the left-hand lower valved coupling 14 may be opened and the left-hand tank refilled, and in the same manner after the tank on the right-hand side has been exhausted it can be refilled while the tank on the left-hand side is again being used. If both tanks are exhausted at the same time, all valves are closed with the exception of the valves 6' in the upper valved couplings 6, which permit the liquid to reach the delivery-pipe 9 and thence to the chemical-hose. When both tanks have been exhausted, valves 6' in the upper valved couplings 6 are closed and the valves 14' in the lower valved couplings 14 are opened, which will permit the water to flow into the tanks and refill the same. At the same time the valve 18 in the vertical valved coupling 17 is opened, which permits a straight waterway from the main supply-pipe 12 through the lower cross-coupling 11 and the vertical coupling 17 to the delivery-pipe 9 and thence to the chemical-hose. This is a decided advantage, inasmuch as the amount of water supplied through the main supply-pipe 12 is adequate to rapidly refill the tanks and at the same time maintain the desired pressure through the delivery-pipe to the chemical-hose. Thus

it will be seen that the tanks can be exhausted separately or simultaneously, and may be re-filled separately or simultaneously and in order to render the chemical-hose serviceable 5 while the tanks are being simultaneously re-filled a direct waterway is maintained from the main supply-pipe to the delivery-pipe 9, thereby keeping up a constant flow of liquid through the chemical-hose at all times, whether 10 from the chemical-tanks or direct from the main supply-pipe.

Having thus described my invention, the following is what I claim as new therein and desire to secure by Letters Patent:

15 The combination of two horizontally - arranged revoluble tanks, horizontal pipes extending forwardly from the axes of tanks, hand - wheels fixed to the horizontal pipes whereby the tanks are revolved, stuffing-boxes 20 in which the outer ends of the horizontal pipes are journaled, and a by-pass located in a vertical plane approximately within the area of

the front end of the tanks, supported by the stuffing-boxes upon the horizontal pipes and consisting of an upper pipe located in the same 25 plane as the horizontal pipes having elbow-couplings, connected with the stuffing-boxes, T-couplings, connected with the elbow-couplings, valved couplings, having valves and connected with the T-couplings and a cross-coupling 30 for a delivery-pipe, connecting the valved couplings, depending pipes connected with the T-couplings, a lower pipe having elbow-couplings, connected to the lower end of the depending pipes, valved couplings having valves and 35 connected to the elbow-couplings, and a cross-coupling for the supply-pipe, connecting the valved couplings, and a vertical valved coupling having a valve and connecting the cross-couplings.

WILLIAM B. DONNELL.
